G. A. LA FONTAINE,
CLIPPER SHEARS,
APPLICATION FILED JUNE 12, 1917.

1,303,072.

Patented May 6, 1919.

UNITED STATES PATENT OFFICE.

GEORGE A. LA FONTAINE, OF LA HABRA, CALIFORNIA, ASSIGNOR OF ONE-HALF TO
OTTO STEINEN, OF LOS ANGELES, CALIFORNIA.

CLIPPER-SHEARS.

1,303,072.

Specification of Letters Patent.

Patented May 6, 1919.

Application filed June 12, 1917. Serial No. 174,219.

To all whom it may concern:

Be it known that I, GEORGE A. LA FONTAINE, a citizen of the United States, residing at La Habra, in the county of Orange 5 and State of California, have invented certain new and useful Improvements in Clipper-Shears, of which the following is a specification.

This invention relates to improvements in 10 clipper shears and has special reference to hair clippers, which are fitted with shear handles, whereby they may be operated like ordinary shears or scissors.

It is an object of the invention to provide 15 double acting clippers with shears or scissor handles extending parallel with the oppositely facing cutters of the devices, whereby the handles are not in the way when cutting hair around the shoulders or neck of a 20 person.

It is also an object of the invention to provide a clipper with a double set of cutting teeth, whereby the clipping may be done in opposite directions, the movable clipper 25 blade and the stationary clipper blade being each provided with shear handles extending longitudinally in the same direction as the rows of cutting teeth upon the clipper blades.

It is also an object of the invention to provide a shears clipper in which a lower and an upper blade are provided, the upper one being held movably against the lower one by means of ball bearings and a tension 35 spring being employed to hold the parts together.

It is a further object of the invention to provide a clipper shears having a stationary blade with cutter teeth on the opposite edges 40 thereof, and to provide a movable blade co-operating therewith, with cutter teeth on the opposite edges thereof, and to provide operating handles for said blades extending along the longitudinal axes of the blades, 45 whereby the handles will not interfere with the cutting operation when the cutters on either side of the device are used.

With these and other objects in view, the 50 invention comprises certain novel constructions, combinations and arrangements of

parts as will be hereinafter more fully described and claimed.

In the accompanying drawing forming a part of this specification:

Figure 1 is a perspective view of a clipper shears embodying the features of the present invention.

Fig. 2 is a longitudinal sectional view taken through the longitudinal axis of the clipper, the shears handles being shown in 60 side elevation.

Fig. 3 is a top plan view of the clipper shears portion thereof, the handle being broken away.

Fig. 4 is a transverse sectional view taken 65 upon the line 4—4 of Fig. 2.

In clippers for ordinary hair cutting as heretofore made, the handles have always been arranged to operate in planes approximating a plane passing horizontally through 70 the clipper blades, and also in a direction parallel with the direction of the clipper edges of the blade. In using such clippers in the cutting of a person's hair, and especially around the neck and lower portions 75 of the head, the handles are nearly always interfered with by the shoulders of the person, and the neck must be bent over and distorted to a considerable extent in order to operate upon the lower edges of the hair. 80

The device of the present invention is not only designed to obviate these difficulties, but is so made that the clipper blades can be operated substantially as easily and freely 85 as the ordinary scissors or shears in the hand of the barber. The device is thus capable of

clipping the hair in either direction, as when the barber passes his hand upwardly over the hair or draws it down again, similar to his operation when he uses the ordinary cutting shears and a guiding comb.

In the accompanying drawing, a preferred form of the clipper has been shown, and the details and features of the invention will now be more specifically described and set forth. In 90

the drawing 5 indicates a clipper holding head, 6 a lower clipper blade, and 7 an upper or movable clipper blade. The clipper blades are preferably made with double cutting edges, that is to say, the said blades are 95 100

formed with tooth shaped cutting points 8 and 9 on the opposite edges thereof. The inner or movable blade 7 is also provided with cutting teeth 10 and 11, extending 5 along the opposite edges thereof.

The head 5, is arranged to extend along over the median lines of said clipper blades thus coming between the rows of teeth, so that the said teeth project outwardly from 10 beneath the said head and opposite sides of the instrument. The cutting teeth of the upper and lower blades are ground to a close even fit upon each other, so as to cut the hair with a shear cut, as the upper blade is moved 15 back and forth upon the lower one in the well known manner customary with hair clippers. The lower or stationary clipper 6 is held with respect to the head 5, by means of a central bolt 12, the lower end of which 20 is provided with a head seated in the lower clipper blade, while the upper end projects above the head 5, and is screw threaded at 13 to receive a tension nut 14. A spring plate or washer 15 is interposed between the said 25 nut 14 and the head 5, so that the parts may be clamped together under a yielding spring action. The outer end of the blade is also steadied and prevented from twisting around the bolt 12 by means of a pin 16, 30 which depends from the end of the head 5 and engages a socket or hole 17 in the end of the lower blade.

The movable blade is mounted between the stationary blade 6 and the under side 35 of the said head 5, and the cutter edges thereof bear upon the cutter edges of the stationary blade, the central inner surface of the said blades being preferably cut away at 18 and 19, as clearly shown in the drawing. The central portion of the head 5 is provided with a longitudinal recess 20 upon its under side which receives and guides upwardly extending projections 21 and 22 formed upon the upper or movable blade 40 along the central line thereof. The upper blade is thus guided in moving back and forth over the lower one. The upper blade is also provided with a central longitudinal slot 23 to accommodate the bolt 12. At the 45 sides of the elongated recess 20, bearing grooves are secured in the under surface of the head 5, and ball bearings 24 are mounted therein and arranged to bear upon the upper surface of the movable blade, whereby the 50 said blade can be moved without much friction and will operate very easily. The movable blade is also provided with a recess or aperture 25 outside the projection 21, which is adapted to receive a short operating lever 55 arm 26, which projects from the inner end of the handle 27. The head 5 is formed with an enlarged bifurcated portion at the handle end thereof affording two ears 28 between which the enlarged end 29 of the 60 handle 27 may be fulcrumed. A pivot bolt 65

30 is passed through the said ears and the enlarged portion 29 to form the fulcrum of the handle. The head 5 also has a handle 31 forming an extension thereof beyond its bifurcated portion, the said handle extending in substantially the same longitudinal direction as the head 5. The outer ends of the handles 27 and 31 are provided with the usual finger receiving rings 32 and 33, through which the fingers of the operator 70 may be inserted for operating the device. The movement of the handle 27 operates to cause the lever arm 26 to reciprocate the upper blade longitudinally and to move its cutter edges back and forth over the cutter 80 edges of the stationary blade.

If desired, the spring washer plate 15 may be provided with a projecting spring arm 34 arranged to extend downwardly between the ears 28 and to bear against the lever arm 85 26 of the handle 27, tending to separate the handles of the clippers to some extent. It is not usually made to entirely open the handles, but is preferably made strong enough to render the movement of the 90 handles very easy, especially in the opening thereof. By this means the action of the instrument is made substantially as easy and free as the movement of the ordinary shears in the hands of the barber or other operator. 95

In the use of the instrument, the barber grasps the handles in the same manner that he would the handles of scissors, and in trimming the hair he moves the instrument sidewise instead of longitudinally, the same 100 as he would the scissors, by reason of the fact that the handles extend longitudinally from the end portions of the clipper blades. The clippers can thus be readily operated for cutting hair in either direction, that is 105 to say, when passing the instrument upwardly from the neck over the head, or downwardly again with a substantially continuous operation. Also by reason of the arrangement of the handles with respect to 110 the clipper blades, the handles do not interfere or come in contact with the shoulders of the person having his hair cut, and the head and neck do not have to be bent out of normal position. The device can be economically made and will be found exceedingly 115 useful in trimming the hair of a person, especially about the neck and lower portions of the head. In the same way, it is useful in trimming the beard or mustache of a person. 120

What is claimed is:

1. In a hair clipper having a stationary head with a handle extended therefrom, a stationary cutter blade spaced therefrom 125 and held thereon, and a removable cutter blade intermediate of said head and said stationary blade, a stud for holding said blades in operative relation to each other, a handle for operating said movable blade, 130

and means held on said stud for holding said handles normally spaced apart.

2. In a hair clipper having relatively stationary and movable blades and a stud for holding said blades in operative relation, a body for supporting said stationary blade, a handle mounted thereon for operating said movable blade, and resilient means carried by said stud and engaging said handle for holding said movable blade normally at one extreme of movement.

3. In a hair clipper having a body pro-

vided with relatively movable cutting blades, a stud supported in said body for holding said blades in operative relation, 15 means for operating said blades, and means supported on said stud for resiliently engaging said blades and said operating means, whereby said operating means, when depressed, may be automatically restored to normal position.

In testimony whereof, I have hereunto set my hand.

GEORGE A. LA FONTAINE.
